[57] **CLAIM**

The ornamental design for a motorcycle tire, as shown and described.

DESCRIPTION

FIG. 1 is a front-elevational view of my novel motorcycle tire showing my new design, it being understood that the tread pattern is repeated throughout the circumference thereof and the opposite side is the same as that shown;

FIG. 2 is a perspective view thereof;

FIG. 3 is a side-elevational view thereof; and,

FIG. 4 is an enlarged fragmentary front-elevational view thereof, showing a detail of the novel tire tread.
